(57) **CLAIM**

The ornamental design for a suction nozzle for vacuum cleaner, as shown and described.

DESCRIPTION

1. Suction nozzle for vacuum cleaner

1.1 is a perspective view of a suction nozzle for vacuum cleaner, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof;

1.7 is a bottom plan view thereof; and

1.8 is a perspective view thereof, wherein the diagonal line at the center of the front lower face represents an LED lamp. The broken line shown in figures 1.1 through 1.6 and 1.8 is for the purpose of illustrating portions that do not form a part of the claimed design.
